CLAIM

I claim, the ornamental design for the sling for leg support, as shown and described.

DESCRIPTION

FIG. 1 is a front elevational view of the sling for leg support showing my new design;

FIG. 2 is a rear elevational view of the sling for leg support thereof;

FIG. 3 is a left-side elevational view of the sling for leg support thereof;

FIG. 4 is a top plan view of the sling for leg support thereof; and,

FIG. 5 is a perspective view of the sling for leg support thereof.

The straps are shown broken away to indicate they have no specific length.
